SELECTIVE NAUGHT BLOCK MECHANISM
FOR CARD OPERATED MACHINESHarold P. Mixer, Rockville Centre, N. Y., assignor
to Remington Rand Inc., New York, N. Y., a
corporation of Delaware

Application October 14, 1948, Serial No. 54,388

2 Claims. (Cl. 101—93)

1

This invention relates to naught block mechanism for punched card statistical or accounting machines, and more particularly to an improved control means for such mechanism.

The function of a naught block mechanism in a machine such, for example, as the tabulator disclosed in the patent to John Mueller, 2,381,361, is to suppress printing and adding in selected columns at certain predetermined times, which function it accomplishes by preventing the advance of the type racks associated with those columns.

The control means for such naught block mechanism include devices to pre-set said naught blocks active or inactive, and means controlled by the presence of a special perforation in a card being processed by the machine to actuate said naught blocks. However, the control means used heretofore have been found inadequate for certain of the complex applications handled by these machines.

Such an application is one in which it is required that items entered in a certain field of the card be characterized by a control perforation representing the month of its entry, and that said items be printed in one of four fields of a printed form according to whether its characterizing control perforation represents a month during the first, second, third, or fourth quarter of a year.

This results, of course, in that a different control perforation is used to represent each of the twelve months of the year, and that the wiring unit of the machine must transmit the information from that one field of the card to all four fields of the printed form. Furthermore, the naught block mechanism must be such as to suppress printing in three fields of the paper under control of any one of nine control perforations, while allowing printing in a fourth field.

It is the principal object of the invention to provide control means of increased capacity and versatility for naught block mechanism of the type involved.

It is a further object of the invention to provide said control means with a plurality of devices manually settable so as to produce a variety of results.

Another object of the invention is to construct said control means so as to permit the actuation of said naught block mechanism under control of any of a variety of control perforations in a card.

Other objects and structural details of the invention will be apparent from the following description when read in connection with the accompanying drawing, wherein

2

Fig. 1 is a fragmentary front to rear vertical section of a machine embodying the mechanism of the invention;

Fig. 2 is a fragmentary rear view showing the mechanism of the invention with the cooperating parts;

Fig. 3 is a detail view similar to a part of Fig. 1 with certain movable pieces in operated position; and

10 Fig. 4 is a diagrammatic view illustrating the transfer of information from a plurality of record cards to a business form by the use of the invention.

For clarity and brevity of description, the invention will be disclosed as applied to a naught block mechanism as used in a tabulator of the type disclosed in the above cited patent to Mueller, it being understood, of course, that the invention is not restricted to use with that machine.

20 In that machine cards are gang sensed by a sensing mechanism situated immediately below the interchangeable wiring unit 25 (Fig. 1) with the result that, when a perforation is detected in any index position, a corresponding push rod 26 in the lower part of said wiring unit is elevated, there being one of said push rods corresponding to each perforation position of a card. The push rods 26, in turn, actuate Bowden wires 27, which elevate plungers 28 at the other extremity of the wiring unit. The plungers 28 each elevate a permutation bar 30, allowing one of several stops 31 to advance and arrest the upward advance of a type rack 32 through the medium of a stepped block 33 on the rear edge thereof. There are a large number of type racks across the machine, and they are restored to and held in the normal zero position by a restoring bar 29 acting on the upper edges of the blocks 33.

25 The push rods 26 and plungers 28 may be of any suitable sort, those shown being preferred because of their large capacity for cross wiring without recourse to Y-wires. The push rods 26 are provided with holes or walls to receive the ends of four Bowdens. Thus, data entered into one push rod may be printed in four places across the paper without using Y-wires. The plungers 28 have wide lower ends adapted to receive three Bowdens, and in order to have their upper ends of the same spacing as the permutation bars 30, 30 each of said plungers is arranged diagonally with respect to the push rods 26. Thus, information from three push rods 26 can be printed in the same position on the paper at different times.

Below the lowermost stop 31 in each position 35 across the machine is another stop 34, not ef-

fected by the permutation bars 38, and adapted to cooperate with a step 35, on the block 33. At its rearmost end, the stop 34 is pivoted to the upright arm of a bell-crank 36, biased clockwise by a spring 37 to hold said stop normally away from step 35. However, if one of said bell-cranks be rocked counter-clockwise, its stop 34 will be projected into the path of step 35 of the associated type rack, and when the restoring bar moves upward, that type rack will be held in normal zero position.

The means whereby the bell-cranks 36 are rocked counterclockwise is the naught block mechanism and will now be described.

The framing of the wiring unit 25 at its upper end includes a rear cross frame bar 38 (Figs. 1, 2, and 3) to which, in whatever positions desired, are secured the naught block units. Each naught block unit is supported by a sheet metal bracket 40 having a flange secured to the side bar 38 by screws 41. Pivoted at 42 to the bracket 40 is a short bar 43 having secured to its upper edge a sheet metal plate 44, bent at its rear end as shown in Figs. 1, 2, and 3. This bent portion of the plate 44 underlies the rounded ends of the horizontal arms of a plurality of the bell-cranks 36, in the illustrated instance, to the number of four.

It is evident that if the bar 43 be rocked counterclockwise about its pivot, the type racks 32 controlled by the plate 44 will be restrained from rising and nothing will be printed in those columns. Such counter-clockwise movement of the bar 43 is limited by the forward (leftward in Fig. 3) edge of the plate 44 coming into contact with the flange of bracket 40.

The means whereby the block 43 is rocked counter-clockwise will now be described.

An upright link 45 underlying the plate 44 has in its upper end a slot 46 engaged by a headed pin 47 in the bracket 40, and has near its lower end a headed pin 48 held in the left hand end of a cam slot 50 in a sliding member 51 by left and right hand (Fig. 2) springs 52 and 53. The member 51 is guided for up and down movement by headed pins 54 and 55 therein which engage forward and rear vertical slots in the bracket 40 (Fig. 3). The member 51 is normally held in its lower position by a spring 56 which engages the pin 54. At its forward end the member 51 is provided with an ear 57 acted upon by a plunger 58 slidably mounted in a housing 60 secured to an ear of the bracket 40.

The construction is such that if the plunger 58 be moved upward, it raises the member 51 and thereby the link 45, which rocks plate 44 and the associated bell-cranks 36 to disable the type racks controlled by said bell-cranks. The parts are shown in their normal position in Fig. 1 and in their operated position in Fig. 3.

In order to disable the mechanism just described so that the bell-cranks 36 will not be rocked even though the plunger 58 is elevated, the lower end of link 45 is formed into a finger piece 61 by which the link 45 may be drawn from its active position, shown in full lines in Fig. 3, to its disabled position, shown in dot and dash lines in that figure, the pin 48 in said link sliding in the slot 50. Said slot is so formed that when the pin 48 is moved to the upper rearward end thereof, the upper end of link 45 is lowered to such a degree that when the member 51 is raised by plunger 58, said upper end does not rock plate 44 sufficiently to affect the bell-cranks 36. When 75

5 moved to its disabled position, the link 45 is held there by the springs 52 and 53.

Whereas only one unit has been described, any desired number of such units may be secured to the frame bar 38, two being shown in the present instance.

Automatic means to disable the naught block mechanism are also provided, said means including a rock shaft 62 journaled in brackets 59 suitably fastened to the rear of wiring unit 25 at its ends. The shaft 62 may be compared to the shaft 818 of the cited Mueller patent and, like that shaft, is connected with the total taking control mechanism of the machine whereby it may be rocked clockwise in Fig. 3 during each totaling operation of the machine.

When so rocked, an arm 63 on said shaft (Fig. 1) acting on a roller 64 on the lower end of link 45 rocks the latter to a disabled position. The pin 48 in said link does not, however, move all the way to the upper rear end of the slot 50 where it would be held by the springs 52 and 53, but only far enough to disable the link, which is pulled back to active position by said springs when the pressure on roller 64 is relieved at the end of the totaling operation.

There is, of course, an arm 63 associated with each naught block unit, two such arms being shown in Fig. 2.

30 The means provided by the invention to actuate the plunger 58 to operate the naught block unit will now be described.

Straddling each naught block unit is a control unit comprising left and right hand (Fig. 2) frame plates 65 and 66, loosely mounted on the shaft 62 and rigidly connected together by a forward slotted plate 67 and a rearward comb plate 68 (Figs. 1, 2, and 3). At its forward end the control unit is supported by a block 70, an extension 71 of the plate 65 resting on said block in the normal position of the parts shown in Fig. 1.

It is to be noted that in this normal position the upper edge of the slotted plate 67 is in contact with the lower end of plunger 58. Thus, if the control unit is rocked clockwise the plunger 58 is elevated.

The block 70 is suitably spaced beneath and supported by a flange 72 bent off from a frame plate 73 fastened to the bar 38. As will be seen in Fig. 2, the plate 73 is yoke shaped, the flange of frame plate 73 being secured to bar 38 in the space between the arms thereof. Anchored in the block 70 are the casings of a series of Bowdens 71, in the present instance to the number of twelve, one from each of the push rods 26 in two columns. The columns used for this purpose are, of course, those corresponding to the columns of the record card set aside for the purpose of control holes, which columns may be located anywhere on the card. In register with the inner wire of each such Bowden 71 is a plunger 74 extending through holes in the flange 72 and spring urged downward against the block 70.

63 Between the side plates 65 and 66 are mounted a series of interponents 75, one for each of the plungers 74. At their forward ends said plungers pass through the slots in plate 67, and near their rearward ends are supported and guided by the comb plate 68. At their rearward ends the interponents are formed into finger pieces 76, alternate finger pieces being bent upward for convenience of manipulation. Thus, in the present instance, as shown in Fig. 2, there are two tiers of six finger pieces 76 extending rearward from each unit. Near its mid-point each interponent

is provided with a retaining hump 17 held on the one side or the other of a rod 18 secured in the side plates 65 and 66 by a spring 80.

In Fig. 1 the interponents 75 are shown in disabled position with the hump 17 positioned behind the rod 18, but in Fig. 3 the interponents are shown in active position with the hump forward of said rod.

When an interponent 75 is moved to active position, the forward end thereof is moved into the path of movement of the associated plunger 14. When that plunger is actuated by its Bowden 27 the entire control unit is rocked clockwise, the motion of the individual interponent 75 being transmitted to the rest of the unit through the plate 81, through a slot in which said interponent passes. Rocking the control unit actuates the naught block unit through plate 67 and plunger 58, as described hereinbefore.

It will be noted from the foregoing that if any one or more of the interponents 75 in a unit is set active and the associated Bowden or Bowdens 27 actuated, then the associated naught block mechanism will be operated.

The described control mechanism can be set up to provide for a great many modes of operation of the machine, but, for brevity, only one such set up, and the resultant mode of operation of the machine, will be described.

The accounting problem to be solved by said mode of operation is as follows:

When running a group of cards through the tabulator, it is desired that information contained in a certain field of the card, and characterized by a control hole representing the month of its entry, be printed in one or the other of four fields of a printed form in accordance with which of the four quarters of a year said month is a part. That is to say, it is desired that information characterized by the control holes for January, February, or March, be printed in one field of the form, and information characterized by the control holes for April, May, and June, be printed in a second field of the form, etc.

To this end, the push rods 26 in the field of the wiring unit corresponding to that field of the card under discussion each coat with four Bowdens 27, which at their upper ends actuate like plungers 28 in four different fields. Thus, information entered into this field of the push rods 26 would be transmitted to four different fields of plungers 28. However, in order that such information will be printed in but one field of the form, each of said four fields is provided with a naught block unit, which units, as presently will be described, are actuated selectively to prevent printing in but one field at a time. This is shown diagrammatically in Fig. 4 where information from card #1 is shown printed in the "first quarter" field of the form, information from card #2 in the "second quarter" field, etc.

The push rods 26 in those columns set aside for the control perforations representing the twelve months also coat each with four Bowdens 27, which, however, do not lead to the plungers 28, but to a plunger 74 in each of the four control units. It will be remembered that there are twelve plungers 74 in each unit, and each is actuated by one of the push rods 26. Thus, there is a corresponding push rod 26 and plunger 74 for each of the twelve control perforations, and when such a perforation is sensed, the like plungers 74 in each of the four units are actuated.

In each control unit all of the interponents 75, except those cooperating with the three plungers

14 representing the months of that quarter year with which said unit is associated, are set active.

In the control unit associated with the type racks which print in that field of the paper set aside for the first quarter year, the 4-12 interponents 75 are set active, in the "second quarter control unit" the 1-3 and 7-12 interponents 75 are set active, in the "third quarter control unit" the 1-6 and 10-12 interponents are set active, and in the "fourth quarter control unit" the 1-9 interponents are set active.

It will readily be perceived that when a control perforation is sensed, three of the control units will be actuated to prevent printing in their associated fields, but the fourth unit, which is associated with the quarter year of which the month represented by said perforation is a part, is not actuated, and printing does occur in that field of the form.

Assuming that card #1 (Fig. 4), which contains a control perforation representing the month of March, has just been sensed, the operation is as follows:

The information contained in the card is transmitted to the permutation bars 30 in four different fields by the wires 21. Elevation of the push rod 26, allied with the control perforation, also actuates four Bowdens 27 which, at their other ends, elevate the March or "3" plungers 74 in each of the four control units. In each unit, except the "first quarter unit," elevating the "3" plunger 74 in turn elevates the plunger 58, through the active "3" interponent and the bar 67 (see Fig. 3). The plunger 58 in turn elevates member 51, link 45, and plate 44, the last of which rocks the associated bell-crank 36 to lock down the type racks 32. Therefore, as shown in Fig. 4, the said information is not printed by the type racks associated with the "second," "third," and "fourth" quarter fields of the form.

In the "first quarter control unit" the "3" interponent 75 is not set active, so that the elevation of the allied "3" plunger 74 is without effect, and the type racks 32 associated with said unit rise and print said information as shown in Fig. 4.

The operation of printing information from cards containing control holes representing months in the "second," "third," and "fourth" quarters is the same as just described, except that different naught block units are actuated in each case. In Fig. 4, card #2 contains a control hole for May, card #3 a control hole for August, and card #4 a control hole for November; and the information from said cards is shown printed in the "second," "third," and "fourth" quarter fields, respectively, of the form.

In the machine to which the invention is here shown applied, the type racks 32 are used not only for printing, but also for actuating accumulators. This being so, the information printed by said racks is also added into the accumulators; and when the machine executes a totaling operation to read out the total of the amounts registered in said accumulators, it is desired that such totals be printed in all four fields, regardless of whether the plungers 74 and 58 are elevated at the time. It is to this end that the arms 63 are provided, said arms being rocked during each totaling operation to disable all of the naught block units.

While there is above described but one embodiment of the invention, it is possible to produce still other embodiments without departure from the inventive concept above disclosed, and it is, therefore, desired that only such limitations

shall be imposed on the appended claims as are stated therein, or required by the prior art.

What I claim as new, and desire to secure by Letters Patent, is:

1. In a machine of the class described, the combination of a sensing mechanism, type racks advanced differentially under control of said sensing mechanism, normally disabled stops to prevent advance of said type racks, means including a first plunger to enable one or more of said stops, a sliding member actuated by said plunger, a push link operated by said member and a plate cooperating with one or more of said stops and actuated by said push link, a bar to actuate said first plunger, a series of interponents each manually settable active or inactive to operate said bar, and a series of second plungers each actuated under control of said sensing mechanism to operate one of said interponents.

2. In a machine of the class described, the combination of a sensing mechanism, a removable wiring unit including a series of rows of push rods actuated selectively by said sensing mechanism and one or more Bowdens actuated by each of said push rods, type racks advanced

10 15 18 differentially under control of certain of said Bowdens, normally disabled stops to prevent advance of said type racks, a plurality of means mounted on said removable wiring unit each to enable one or more of said stops and each including a first plunger, a plurality of swinging frames mounted on said removable wiring unit each including a bar to actuate one of said first plungers and a series of interponents manually settable active or inactive to operate said bar, and a plurality of series of second plungers to operate said interponents, like plungers of each series being actuated by a common push rod through its associated Bowdens.

HAROLD P. MIXER.
